UNITED STATES PATENT OFFICE.

LAURA FLENTYE, OF WILMETTE, ILLINOIS.

IMITATION CHRISTMAS TREE.

Application filed April 7, 1926. Serial No. 100,295.

This invention relates to imitation Christmas trees and the like and is fully described in the following specification and shown in the accompanying drawing, in which:

5 Figure 1 is a vertical sectional view on the line 1 of Fig. 2;

Fig. 2 is a slightly enlarged horizontal section on the line 2—2 of Fig. 1;

10 Fig. 3 is a similar view of the sheets of paper lying flat; and

Fig. 4 is a view similar to Fig. 2 showing a modified form of the invention.

The embodiment illustrated comprises a small imitation Christmas tree having a base 10 from the center of which rises a center post or standard 11 to which is secured a series of sheets of heavy paper 12. These are preferably stitched at 13 on both sides of the post 11 so as to secure them to the post.

15 20 This stitching is preferably so done that the post 11 is afterward inserted when the device is being assembled. Likewise the post is removable from the base 10 so that with the paper sheets 12 stitched at 13, as shown in Fig. 3, the whole can be packed flat and thus occupy very little space.

25 The base 10 is preferably round as shown in Fig. 2, with an annular lip 14 which is provided with a series of radial slots 15 into 30 which the outer ends of the sheets 12 may be inserted.

35 In assembling the device, the post 11 is inserted into the opening 11^a between the stitching 13, and the lower end of the post 40 inserted in the central opening in the base 10. The operator then bends the several sheets 12 back as shown in Fig. 2, inserting one of the outer ends of these sheets in each 45 of the slots 15. When so completed and the sheets pressed down to the bottom of the slots, the whole will assume the general form and appearance of a small evergreen tree. For this purpose the paper sheets are preferably made of a suitable green paper and tinsel, glass balls or other decorative material may then be secured thereon as desired.

50 The sheets 12 are all preferably of apparently the same size and contour, but there should be some variation in the size and shape of the slots representing branches so as to relieve the whole from too great a monotony.

If desired, the central post 11 may be dispensed with as soon as the use of a base such

as that shown would render the whole sufficiently stable as to stand upright, particularly if the ends of the leaves were glued in the slots 15. Where the post 11 is omitted a single line of stitching 13 would then be sufficient.

55 60 In Fig. 4 is shown a modified form of the device in which, if desired, the notched ledge 14 may be dispensed with and a plain paper 10^a used. In this case the spread or fanning of the sheets 12^a could be accomplished by 65 securing together the two ends of the outer sheets 12^b as by means of glue 16 and then be secured together as at 12^c and 12^d, and the ends of the branches at intervals around the tree, until the whole gives a nearly uniform 70 spacing for the several sheets.

75 At these points also if desired may be attached tinsel 17 or the like which may be secured thereto by means of the glue 16 or ornaments 18 of glass or other material may be secured thereto by means of cord 19 or the like.

80 While I have shown and described but a single embodiment of this invention, it is to be understood that it is capable of many modifications. Changes therefore in the construction and arrangement may be made which do not depart from the spirit and scope of the invention as disclosed in the appended claims.

85 I claim:

1. An imitation tree comprising a base, a plurality of sheets of paper cut to represent the silhouette of a tree and secured together along a central axis, said sheets being spread at their outer edges, and means for holding said sheets in the spread position.

90 95 2. An imitation tree comprising a base, a plurality of sheets of paper cut to represent the silhouette of a tree and secured together along a central axis, said sheets being spread at their outer edges, and means on said base for holding said sheets in the spread position.

100 105 3. An imitation tree comprising a base, a plurality of sheets of paper cut to represent the silhouette of a tree and secured together along a central axis, said sheets being spread at their outer edges, a central post secured to said base and to said sheets, and means for holding said sheets in the spread position.

LAURA FLENTYE.
